PROTECTION FENCE FOR RAILROADS

Edward G. Baumann, Aspinwall, Pa.

Application August 1, 1934, Serial No. 737,873

12 Claims. (Cl. 246—121)

This invention relates to protection fences for railroads, and more particularly to fences used for guarding a right-of-way against falling objects from neighboring embankments, as well as for warning approaching trains by signal in the event that a large object strikes the fence, or a land-slide occurs, or other conditions exist which render the track dangerous.

One object of the invention is to provide a comparatively simple and inexpensive slide protection fence of this character, with the parts so designed that they may be assembled and removed with facility.

Another object of the invention is to provide, in association with such a fence, an improved circuit breaker for causing a warning signal to be displayed when the fence is disturbed, and to provide means for operating the circuit breaker which are responsive to the impact of large objects but are not affected by expansion and contraction of the fence netting or by relatively insignificant disturbances of the fence.

Another object of the invention is to provide a slide protection fence which does not require a special foundation, which may be installed on telegraph and telephone poles, and which may be constructed of any desired height, and of such a design that the fence posts may be spaced wide apart with a single circuit breaker covering a relatively long fence panel.

Another object of the invention is to provide means for indicating the condition of a circuit breaker, such means being visible at a distance and operated automatically as an incident to the operation of the circuit breaker.

Still other objects and advantages characterizing this invention will become more fully apparent from the detailed description, hereinafter set forth, of one embodiment or example of the invention having reference to the accompanying drawings. Of the drawings:

Fig. I represents a front elevation illustrating an installation in which a single fence panel is employed.

Fig. II represents a side elevation of the same.

Fig. III represents a detailed front elevation showing the central portion of the fence at the circuit breaker, and showing the operating rod and indicator in the positions occupied when the circuit breaker is actuated.

Fig. IV represents a detailed view of the circuit breaker, the same being a cross section taken as indicated by the lines IV—IV of Fig. II.

Fig. V represents a cross section of the same, taken as indicated by the lines V—V of Fig. IV, and showing the manner in which the indicator is operated.

Fig. VI represents a detailed view showing the method of suspending the fence from the carrier wire; and,

Fig. VII is a perspective view of a modified form of protection fence composed of a series of tiered panels, one above another, showing the type of construction utilized adjacent to a relatively high and steep embankment.

In the example of my invention shown in Figs. I, II and III of the drawings, there is selected for convenient illustration a slide protection fence which consists of a single panel of netting as indicated at 1. It will be apparent from the description hereinafter that the fence may be made up of a number of superposed panels, the proportions and character of which may be varied very considerably. As shown in Figs. I and III, the fence is supported upon end posts 2, and intermediate posts 3 including a central post 3a which carries a circuit controller box 4. The posts do not require any special foundation, and at times it may be convenient to utilize the ordinary telegraph and telephone posts for supporting the protection fence of this invention. Where special posts are provided, the end posts 2 are preferably braced by diagonal stays 5. Extending between the end posts 2 are carrying wires 6 and 7, such wires being relatively taut and held in tension by means of spiral springs 8 located at each end. The springs 8 are in turn fastened to the end posts 2 by removable means which may take the form of hook bolts 9. The upper and lower carrying wires 6 and 7 are supported upon the intermediate posts 3 and 3a by fastening means which may also take the form of hook bolts 14 or clamps 14a, or in the event that the fence extends around a sharp curve, eye-bolts may be used which will project the carrying wires a substantial distance forwardly of the intermediate posts.

The netting 1 is suspended between the upper and lower carrying wires 6 and 7, and is unattached to the intermediate posts 3 and 3a. A suitable method of attaching the netting 1 to the carrying wires 6 and 7 is to employ rings 15 in the manner illustrated in Fig. VI, such rings sliding freely upon the wires 6 and 7 and engaging the top and bottom parallel longitudinal wires of the netting 1. At the ends of the netting 1 vertical spacer bars 16 are employed, and such bars are temporarily secured to the end posts 2 by means of a hook bolt 17 which engages a band 18 disposed substantially at the center of the spacer bar 16. The described construction permits the netting to be easily erected and removed. Moreover, it will be particularly noted that the netting 1 is secured only at its ends, and that its intermediate portion has capacity for limited longitudinal movement in sliding engagement with the carrying wires 6 and 7. While the wires 6 and 7 are relatively taut, the netting 1 is relatively slack, and hence capable of considerable longitudinal movement at its central por-

tion under the impact of large falling objects. Ordinary farm fence may be conveniently utilized for the fence panels. Desirably, I employ netting which is slightly kinked as is customary 5 with farm fence, for such kinks serve to permit uniform expansion and contraction under temperature changes without appreciable movement of the central portion of the netting.

At the center post 3a an operating arm 20 is 10 provided for actuating a circuit controller housed in the box 4. The operating arm 20 in its preferred form extends substantially across the netting 1 and is fastened thereto at spaced points from top to bottom by fastening clips as indicated at 21. The operating arm 20 is pivoted at 22 to a bracket which may be placed at the bottom of the circuit controller box 4, or which may be more directly attached to the center post 3a. Preferably the operating arm 20 is made up 15 of a series of pieces including a strip of wood 23 which is relatively weak and will give way under severe stress, thus at times saving the parts of the circuit controller from breaking.

As shown more clearly in Fig. IV, the upper 20 portion of the operating arm 20 terminates in a flat end 24 which extends between the opposite curved ends of a pair of levers 25 pivoted at a common point 26. The upper arms of the levers 25 engage rollers 27 mounted on rocking levers 28, which in turn are pivoted at 29 to fixed 25 brackets 30. The upper ends of the rocking levers 28 are connected by links 31 to movable contact members 32. The movable contact members 32 are normally held in engagement with fixed 30 contact members 33, such members being electrically connected with terminals 34. It will be noted that there are two sets of contact devices, so that a swinging movement of the upper end 35 of the operating arm 20, either to the left or to the right, will cause one of the movable contact members 32 to separate from its companion contact 33, as shown in dot-and-dash lines in Fig. 40 IV. The contacts 32 and 33 serve to open and close signal circuits of the ordinary type employed on railroads, and as such circuits are well known and not a part of this invention, they are 45 not described herein.

The sensitivity of the circuit controlling apparatus may be adjusted by the amount of lost 50 motion permitted in the operating levers, and by the shape of the upper end 24 of the operating arm 20. Ordinarily it is undesirable to have the circuit breaker operate as a result of every slight movement of the netting 1, such as caused 55 by small sticks and stones striking it, and accordingly the operating levers are adjusted to prevent such operation. Obviously, however, if it is desired to have a circuit controller operate and the warning signal displayed whenever any 60 movement of the fence occurs, this may be accomplished by reducing the amount of lost motion permissible and thus rendering the apparatus more sensitive.

For the purpose of producing a visible indication 65 showing the condition of the circuit controller, there is provided an indicator 38 in the form of a vertical bar, shown clearly in Figs. III and V, which is adapted to slide up and down through the bottom 39 of the circuit controller box 70 4. The indicator bar 38 terminates at its upper ends in a narrow hook shaped projection 40 which normally rests on the flat upper end 24 of the operating arm 20. When the operating arm 20 is in a vertical position, as indicated in 75 Fig. IV, the indicator bar 38 is held in raised

position and is invisible. Movement of the lower portion of the operating arm 20 either to the right or to the left releases the hooked projection 40, causing the indicator bar 38 to project beneath the bottom 39 of the circuit controller box 4. Conveniently the indicator bar 38 is painted with a bright color, or a color contrasting with that of the box 4 and post 3a, so that it is readily visible at a distance.

In Fig. VII of the drawings, there is shown a 10 slide protection fence comprising a series of panels 1 superposed one above the other and suspended from carrying wires 6 and 7 extending between upright supports 41 in the form of telegraph and telephone poles. Such a construction 15 constitutes merely a duplication of the netting and associated apparatus illustrated in Figs. I, II and III.

The operation of the apparatus of my invention is as follows: When the netting 1 is disturbed by impact with large objects, such as 20 trees, stones, or the like, or when it is carried away by a land-slide, the initial impact will cause a movement of the netting in the direction of its length along the carrying wires 6 and 7, 25 the direction of movement being dependent upon whether the disturbance occurs at one side of the center post 3a or at the other side. It will be observed that regardless of whether an object strikes the netting near the top or the bottom, 30 there will result a swinging movement of the lower portion of the operating arm 20, for this arm is fastened to the netting at a plurality of points from the top to the bottom of the netting. Swinging movement of the lower portion of the 35 operating arm 20 imparts a like movement to its upper end 24. The upper end 24 of the operating arm 20 in turn causes one of the levers 25 to swing. The outward movement of the upper end of the lever 25 in turn causes an outward 40 movement of the lower end of the rocking lever 28 and an inward movement of its upper end. This in turn causes the link 31 to be drawn inwardly, separating the movable contact 32 from the stationary contact 33. As an incident to the 45 operation of the circuit controller, the indicator bar 38 will fall by gravity. Under these conditions the apparatus will take the form illustrated in Fig. III, and there will be displayed along the track a signal, warning approaching trains of 50 existing danger.

The novel means of supporting the netting which characterizes my invention is inexpensive in construction, and involves many important advantages. The netting is continuous from one 55 end post to another, there being no gaps through which large objects may pass without disturbing it. Moreover, the length of the netting may be extended to a considerable distance from each side of the intermediate support upon which the circuit controller is mounted, thus reducing the number of circuit controllers required in a long protection fence. A further important advantage obtained by the use of this invention resides in the fact that the panels of a built-up fence are 60 readily removable. Accordingly, ditching operations which periodically occur along railway 65 track may be conducted with only a short time required to prepare for such operations, by removal of the lower panels of the fence.

While I have described my invention in some detail with reference to a specific example thereof, it will be apparent that many changes may be made in the construction of the fence herein described and illustrated without departing from 70 75

the spirit of my invention as defined in the annexed claims. It will be particularly apparent that the netting may take many different forms and that I do not mean to limit myself to the use of wire mesh, but may employ other devices which will respond to the impact of falling objects in like manner.

Having thus described my invention, I claim:

1. A protection fence for a railroad comprising spaced upright supports, a wire extending between said supports, a netting suspended on said wire with the ends thereof secured to said supports and the intermediate portion having capacity for movement longitudinally along said wire, an additional upright support disposed near the center of said netting, a circuit breaker thereon, and means responsive to movement of the netting in either direction along said wire for operating said circuit breaker.

2. A protection fence for a railroad comprising end posts, carrying wires extending between said end posts, a netting suspended between said wires and extending continuously from one end post to the other, said netting having its ends secured to said posts and having its intermediate portion supported solely on said wires with capacity for movement longitudinally therealong, a circuit breaker disposed between said end posts, and means responsive to movement of the netting along said wires for operating said circuit breaker.

3. A protection fence for a railroad comprising end posts, additional posts intermediate said end posts, a wire extending between said end posts and supported on said intermediate posts, a netting suspended on said wire and extending continuously from one end post to the other, said netting being secured to said end posts but not to said intermediate posts and having capacity for movement longitudinally along said wire, a circuit breaker on one of said intermediate posts, and means responsive to movement of the netting along said wire for operating said circuit breaker.

4. A protection fence for a railroad comprising spaced upright supports, a relatively taut wire extending between said supports, a relatively slack netting extending between said supports and suspended on said wire in sliding engagement therewith, an additional upright support disposed between the supports aforesaid, a circuit breaker thereon, and means responsive to sliding movement of the netting along said wire for operating said circuit breaker.

5. A protection fence for a railroad comprising spaced upright supports, a spring-tensioned wire extending between said supports, a relatively slack netting having its ends secured to said supports and suspended freely on said wire in sliding engagement therewith, an additional upright support disposed between the supports aforesaid, a circuit-breaker thereon, and means responsive to sliding movement of the netting along said wire for operating said circuit breaker.

6. A protection fence for a railroad comprising spaced upright supports, carrying wires extending between said supports, a netting including a series of parallel longitudinal wires cross connected at their ends by vertical spacer bars, said netting being suspended between said carrying wires in sliding engagement therewith and having its spacer bars anchored to said upright supports by removable fastening members and being otherwise unsupported, a circuit breaker disposed between said upright supports, and means

responsive to sliding movement of the netting along said wires for operating said circuit breaker.

7. A protection fence for a railroad comprising spaced upright supports, a carrying wire extending between said supports, a netting suspended on said carrying wire in sliding engagement therewith and secured at its ends to said upright supports, an additional upright support disposed between the supports aforesaid, a circuit breaker thereon, and means for operating said circuit breaker comprising an arm pivoted to said additional support and disposed substantially in the plane of said netting and fastened thereto.

8. A protection fence for a railroad comprising spaced upright supports, a carrying wire extending between said supports, a netting suspended on said carrying wire in sliding engagement therewith, an additional upright support disposed between the supports aforesaid, a circuit breaker, and means for operating said circuit breaker comprising an arm pivoted to said additional support and extending substantially across said netting and fastened thereto at spaced points from the top to the bottom of said netting.

9. In combination with a slide protection fence for a railroad including spaced upright supports and a netting extending between said supports and adapted to move under impact, a circuit breaker having a pair of movable contacts and levers for actuating said contacts, said levers terminating in oppositely disposed ends, and a pivoted operating arm having one portion thereof attached to the netting and another portion extending between the oppositely disposed ends of said actuating levers.

10. In combination with a slide protection fence for a railroad including end posts, an intermediate post and a netting extending between said end posts and in proximity to said intermediate post, said netting being adapted to move in the direction of its length under impact, a circuit breaker mounted on said intermediate post and having a movable contact and a lever for actuating said contact, and an operating arm pivoted to said intermediate post, said arm having one portion thereof extending across and fastened to said netting and having another portion adapted to engage the actuating lever aforesaid.

11. In combination with a slide protection fence for a railroad including end supports, an intermediate support and a netting extending between said end supports and in proximity to said intermediate support, said netting being adapted to move under impact, a circuit breaker mounted on said intermediate support and having an operating arm fastened to said netting and responsive to its movement, a housing for said circuit breaker, and an indicator normally disposed within said housing and adapted automatically to be projected from said housing when the circuit breaker is operated.

12. In combination with a slide protection fence for a railroad including end supports, an intermediate support and a netting extending between said end supports and in proximity to said intermediate support, said netting being adapted to move under impact, a circuit breaker mounted on said intermediate support and having an operating arm fastened to said netting and responsive to its movement, said operating rod being pivoted on said intermediate support, and an indicator normally engaging the upper end of said operating arm and held by it in raised position, said indicator being adapted to fall by gravity when the operating rod is swung about its pivotal point.

EDWARD G. BAUMANN.
